UNITED STATES PATENT OFFICE.

RICHARD PREISS, OF CHICAGO, ILLINOIS.

DESIGN FOR AN AUTOMOBILE RADIATOR CLOSURE.

61,399.

Specification for Design. Patented Aug. 22, 1922.

Application filed January 13, 1922. Serial No. 190 $\frac{1}{2}$. Term of patent 3 $\frac{1}{2}$ years.

To all whom it may concern:

Be it known that I, RICHARD PREISS, a citizen of the United States, residing at Chicago, in the county of Cook and State of Illinois, have invented a new, original, and ornamental Design for Automobile Radiator Closures, of which the following is a specification, reference being had to the accompanying drawing, forming part thereof.

The figure is a perspective view of the automobile radiator closure.

I claim:

The ornamental design for an automobile radiator closure as shown.

In testimony whereof I affix my signature in the presence of two witnesses at 36 W. Randolph St., Chicago, Illinois.

RICHARD PREISS.

Witnesses:

DANIEL A. BRENNAN,
IRENE MARTIN.
